COKE OVEN WITH HORIZONTAL REGENERATORS

Grady Padgett, Beaver, Pa.

Application January 7, 1946, Serial No. 639,560

5 Claims. (Cl. 202—146)

1

This invention relates to improvements in regenerative vertical coke ovens heated by horizontal flues, and has for a primary object the arrangement of each horizontal flue separate from the other flues, and provided at each of its ends with individual regenerators for alternate use in supplying heated air and gas to the opposite ends of the flue.

In my companion application, Serial No. 492,915, filed June 30, 1943, now Patent No. 2,434,862, I have disclosed a vertical coke oven with a plurality of spaced horizontal flues receiving heated air and gas from the same regenerators arranged vertically at the ends of the flues for substantially the entire height of the oven. The present invention does away with such large vertical regenerators, and enables use of individual regenerators at each end of each horizontal flue wherein the flow of air and gases is more readily and more accurately controlled at various rates of combustion. The present arrangement also provides a combustion system which will produce uniform temperatures over very long horizontal flues and thus makes possible the construction of coke ovens larger than have yet been built, wherein pressure differentials and labor costs may be kept unusually low.

Another object of this invention is the provision of regenerators of comparatively small height wherein air and gases travel in a wave-like movement in a substantially horizontal direction.

A further object is the division of individual regenerators into upper and lower sections, one section delivering heated primary air or mixed air and gas to the adjacent end of its horizontal combustion flue, and the other section delivering secondary air or gaseous mixtures at a point or points along the flue spaced from the flue extremities.

A further object of the invention is the arrangement of control means conveniently near the ends of the coke ovens and clear of the charging and discharging mechanisms, whereby primary and secondary air or air and gas mixtures may be accurately controlled at all rates of combustion and with various fuel gases.

A further object of this invention is the provision of a plurality of superimposed regenerators at the ends of the combustion flues wherein fire-clay slabs are used in the cooler zones of the regenerators, particularly in the horizontal partitions, and silica slabs with their greater expansion are used throughout the walls of combustion flues and in the hotter zones of the regenerators,

2

suitable expansion joints being included in the wall construction.

A further object of the invention is the provision of a method of combustion, particularly useful with horizontal flues in regenerative vertical coke ovens, wherein rich gases are diluted with waste gases in the combustion flues to slow combustion and permit the heat of the flame to be spread over a larger area. The introduction of the rich gas by injection at one end of the flue is utilized to draw the waste gases from the regenerators adjacent the opposite end of such flue for use as a diluent.

Various other objects and meritorious features of the invention will be apparent from the following description taken in conjunction with the drawings, wherein like reference numerals designate like parts throughout the several figures, and wherein:

20 Fig. 1 is a diagrammatic illustration of a battery of two coke ovens embodying my invention, the left half being in plan view and the right half in horizontal section taken substantially on line A—A of Fig. 2;

25 Fig. 2 is a diagrammatic illustration of such battery, the left half being in side elevation and the right half in vertical section, taken substantially on the line B—B of Fig. 1;

30 Fig. 3 is an enlarged longitudinal vertical section through one end of a horizontal combustion flue and associated elements;

35 Fig. 4 is a vertical cross section through the combustion flue and associated distributing flues, taken substantially on line C—C of Fig. 3;

40 Fig. 5 is a vertical cross section through the regenerator at one end of the combustion flue, taken substantially on line D—D of Fig. 3;

Fig. 6 is a detail perspective view showing a multi-walled tile used in the regenerators;

45 Fig. 7 is a vertical longitudinal section through a modified arrangement of combustion flue and associated elements taken substantially on line G—G of Fig. 8;

Fig. 8 is a composite horizontal section through the modification of Fig. 7, the left half being taken substantially along the line E—E and the right half substantially along the line F—F of Fig. 7;

Fig. 9 is an enlarged detail vertical section showing the gas injector nozzle mounting, and

50 Fig. 10 is an enlarged detail section through the nozzle tip.

The battery illustrated in the drawings comprises a plurality of coking chambers 12 and 14 with walls tapered from top to bottom in the cus-

3

tomary manner. A strengthening partition 18 (Fig. 1) is positioned transversely between the walls of each coking chamber 12 and 14 and extends vertically for substantially the height of the chamber, forming a rigidifying member dividing the chamber into two substantially equal parts. It will be appreciated that more than one vertically extending transverse strengthening partition may be arranged in each coking chamber at points spaced longitudinally along the length of the chamber as desired. The coking chambers 12 and 14 are charged through charging doors (not shown) at the top of the chambers and coke withdrawn from the bottom of each chamber in the manner customary with vertical coke ovens. Volatile products from the coke are removed through offtakes 18 (Fig. 2).

Extending horizontally along each side of each choking chamber 12 and 14 are a series of superimposed combustion flues 20 (Figs. 1-4). At each end of each combustion flue 20 is arranged a regenerator 22, herein shown as divided by vertical and horizontal partitions into pairs of upper and lower sections 22A, 22B, 22C and 22D respectively, each containing several horizontally spaced multi-walled tile units 30 (Figs. 3 and 6) over and through which pass waste gases from the combustion flues 20 for heating the tiles and alternately, with periodic reversals, air and lean gases, divided into primary and secondary streams (Fig. 5) which absorb heat from the tiles en route to the combustion flues 20.

Air or lean gas is admitted to the regenerator sections through ports 24, the areas of which are controlled through regulating valves 26, separately turnable each by its handle 28, mounted at a distance from the flues 20, and exteriorly of headers 32 through which air and lean gases reach ports 24. With my present arrangement, it is possible to mount the control valves at the ends of the coke ovens in comparatively cool positions and where their operation will not interfere with the charging of coal or discharging of coke to or from the coking chambers. It will be understood that the drawings, except for the diagrammatic showings in Figs. 1 and 2, are limited to one end of the battery, the structures at the other end being substantially duplicates of those shown.

When heating with lean gas, such gas passes through valved ports 24 into two of the regenerator chambers, as 22A and 22B (Fig. 5) and air enters through the valved ports 24 of the other two of the regenerator chambers, as 22C and 22D, of each combustion flue 20 then being used. Both the air and lean gas are heated as they pass over the tile units 30 in wave-like movements, as will be hereinafter more fully described. At the inner ends of each regenerator 22 the primary air from one lower generator section, as 22D (Fig. 5), mixes with the heated primary gas from the other lower regenerator section, as 22A, inclined passages 34 (Figs. 1 and 5) converging to lead the mixture into the combustion flue 20, and combustion begins.

Air and lean gas are also passed in a similar manner over the heated tiles 30 in the upper or secondary regenerator chambers, as 22B and 22C, but such secondary ingredients are not permitted to mix at the end of combustion flue 20, as do the primary ingredients. Instead, the secondary air and secondary gas are led through independent ducts 36 and 38 respectively (Fig. 4) to a port or ports 40 in the combustion flue 20 spaced a considerable distance inwardly from the end of the flue. As best shown in Figs. 3 and 4, ducts 36 and

4

38 are arranged adjacent the top of each combustion flue 20, being separated from each other by a vertical partition 42 and from the combustion chamber of the flue by a horizontal partition 44. In this manner a combustion system is provided which will produce substantially uniform temperatures over long flues. Combustion takes place along an entire half of the combustion flue 20, this action being facilitated by introduction of gas and air separately at ports 40 spaced from the admission end of the combustion flue, thus retarding combustion until the last port delivers its air. On reversal every ten to thirty minutes the other half of the combustion flue is uniformly heated.

It should be understood that lean gas is not used when rich gas is used, and vice versa. When rich gas is used, air is admitted through all valved ports 24 into all regenerator sections 22A, 22B, 22C and 22D, and rich gas is admitted through a single pipe 46 (Fig. 5) directly into the inlet end of combustion flue 20. In this case, the combustion is delayed and extended by a deficiency of air until the flame reaches the secondary ports 40 and sufficient air for complete combustion is supplied. When the remaining combustible reaches port 40 it is diluted with the products of the primary combustion so that flame propagation is retarded and the heat of combustion thus spread over an extended portion of combustion flue 20. The rich gas may have some diluent, such as waste or stack gases or steam added at the flue near the point where the gas enters. Such dilution prevents carbon formation in the pipes 46 as well as retards combustion so as to enable better control of flame propagation.

I have shown in Figs. 7-10 a modified construction particularly useful with my improved method of diluting the rich gas intake by entraining the waste gases from the regenerators then at the delivery end of the flues. This modification and method will now be described. The rich gas is injected into the combustion flues through a nozzle 48 mounted substantially as shown in Figs. 7-9 in the ends of the flues 20. Rich gas is supplied through suitable pipe lines 50 at one end of the nozzle and the gas is injected through the removable tip 48A (Fig. 10) so as to draw waste gases from the opposite end of the combustion flue, such waste gases passing through the upper return duct 52 across the flue and being entrained by the fast moving gases from the jet 48 into the lower duct 54, a Venturi effect being secured, as at 48B (Fig. 9), to increase the flow of waste gases. Entering the combustion flue 20, the rich gas from jet 48 meets the heated air emerging through passages 34 after travel through regenerators 22, and the mixing of waste gases adjacent the same location eliminates the formation of carbon in the ducts carrying the gas and also retards the combustion, permitting the heat of the flame to be spread over a larger area.

Inspection flues 58 are arranged at opposite ends of flue 20 for observation of the combustion, and the valves for control of admission of air and gases changes as desired to secure maximum efficiency with various gases. The usual reversing mechanism will cut off the gas at one end of the oven and turn it on at the other end, and flows of gas and air are automatically reversed. Suitable valves, as 56 (Fig. 8), may be supplied exteriorly of the oven to control the flow of gas into the nozzles 48.

While this construction and method are particularly designed for use with rich gas, they can also be used with producer and other lean gases

which contain sufficient inerts in themselves to prolong combustion. This modification can also be used in other types of ovens, retorts, furnaces, etc., where the heat economy of regenerators justifies the installation of a reversing mechanism. Its simplicity is apparent, and it should give longer life and greater ease of operation.

In Fig. 6 is illustrated one of the multi-walled tile units 30, and in Fig. 3 is shown a preferred arrangement of such tile units in the regenerator chambers. The tile plate 30A nearest the inlet end of the regenerators extends into the upper wall or partition of the regenerator chamber (Fig. 3), and the tile 30B furthest from the inlet end of the regenerator contacts the lower wall or partition in such regenerator chamber. A series of spaced intermediate tiles 30C are arranged substantially as shown in Figs. 3 and 6 with their extremities progressively differing in heights. This arrangement enables the passage of incoming air and/or gas in wave-like movements in a substantially horizontal stream, while dividing the streams to provide contact with a large surface area of tile within the regenerator chambers. The gas and air in passing to the combustion zone are heated while rising to the top of the tile units in small streams, then pass from top of one tile unit to the bottom of the next tile unit with only side walls controlling the passage from top to bottom. Thus most of the heating is done on the up-passage and there will be no channeling on the down-passage since there is only one channel through which the air or gas must go.

The present construction is practical for use with present-day refractories, silica of a thickness of at least 2 in. being utilized in the hotter zones and fire-clay brick or tile in the cooler zones. With the available height for a horizontal flue about 2 ft., and the temperature differential between inlet and outlet of 900° C. required, a regenerator 15 ft. long and having 15 up-passes through multi-walled tile units 30 would be arranged so that only a difference of 60° C. temperature is needed between the top and bottom of each pass. With the horizontal partitions dividing the upper regenerator chambers 22B and 22C from the lower regenerator chambers 22A and 22D substantially midway between top and bottom of the regenerators, approximately 1 ft. is permitted for up and down travel of the incoming air and gases, and with this space it is possible to keep the temperature differentials well within the insulating properties of the 2 in. horizontal partitions.

While for purposes of illustration I have disclosed the use in each regenerator of a series of multi-walled tile units, it will of course be understood that a series of spaced slabs could be arranged similarly and used in lieu thereof.

Fire-clay slabs 60 (Fig. 3) are used in the horizontal partitions in the cooler zones of the regenerator. These should be used up to where the average temperature is between 500-600° C. The side walls and the horizontal partitions in the hotter zones of the regenerator will be made of silica. Expansion joints, as 62 (Fig. 5), may be suitably arranged in the vertical walls and to take care of the expansion in the horizontal partitions. In the cooler zones of the regenerator stainless steel sheets, as 64, may be arranged in the horizontal partitions between the fire-clay slabs.

As best illustrated in Figs. 1 and 4 I have also built into the walls of the combustion flues 20 a vertical reinforcing by use of spaced integral ribs 66. These ribs aid in supporting the thrust of the

coal charge in the coking chambers 12, 14. In the larger ovens, the weight of the coal charges may run as high as 25 to 30 tons.

In operation, the coking ovens are charged at the top and the coke falls by gravity into suitable discharging apparatus (not shown). The coking chambers are heated from the combustion flues 20, which may use either rich gas as hereinbefore described or any suitable lean gas, such as oven, blue, producer, blast furnace gas or the like. It would also be possible to provide for steaming of the coke near the end of the coking period, for the additional production of gas, and thereby eliminate the necessity for a producer gas plant, with consequent savings in capital and labor costs.

Various controls (not shown) of conventional nature are provided for admitting the combustibles into the regenerators and no description of this phase of the coking oven is believed necessary. On reversal, which may occur periodically every fifteen minutes or thereabouts, the air and gases merely flow in the opposite direction, and the waste products pass through the tile units in the regenerator chambers which had previously been used for inlet or combustibles. Such waste products are discharged through conduits (not shown) leading to collecting mains or stacks in the usual manner.

The simplicity of my improved coke oven will be apparent, and the control of air and any desired gas directly into individual regenerators at the opposite ends of each combustion flue provides a construction capable of accurate control with ready variation whenever desired to meet changes in the heating capacity of the different gases, etc.

I claim:

1. In a regenerative vertical coke oven having a plurality of spaced vertical coking chambers, a plurality of superimposed horizontal combustion flues on both sides of each coking chamber, each combustion flue being independent, and regenerators at each end of each combustion flue, extending substantially the full height of said flue and divided into four sections for separately heating primary and secondary air and gas combustibles for use in the combustion chamber.

2. A regenerative vertical coke oven comprising a plurality of spaced vertical coking chambers, a plurality of independent parallel superimposed horizontal combustion flues on both sides of each coking chamber, parallel ducts interposed between horizontally adjacent combustion flues communicating with the latter at points spaced from the ends thereof, and horizontal regenerator units in alignment with each combustion flue at opposite ends thereof, respectively, each regenerator unit being divided into parallel sections separately communicating with its respective combustion flue and an adjacent duct, the heating surfaces in each regenerator section being arranged to cause the fluid introduced therein to flow across the same in a successive series of parallel vertical paths.

3. The arrangement described in claim 2 wherein means are provided for separately introducing fluid into each of said sections.

4. A regenerative vertical coke oven comprising a plurality of spaced vertical coking chambers, a plurality of independent parallel superimposed horizontal combustion flues on both sides of each coking chamber, a pair of parallel ducts interposed between horizontally adjacent combustion flues each communicating with the latter

at points spaced from the ends thereof, and horizontal regenerator units in alignment with each combustion flue at opposite ends thereof, respectively, each regenerator unit being divided into parallel sections separately communicating with its respective combustion flue and said ducts at separate outlets, the heating surfaces in each regenerator section being arranged to cause the fluid introduced therein to flow across the same in a successive series of parallel paths.

5. The arrangement described in claim 4 wherein means are provided for separately introducing fluid into each of said sections.

GRADY PADGETT.
